(57) **CLAIM**

The ornamental design for a bicycle light, as shown and described.

DESCRIPTION

FIG. 1 is a perspective view of a bicycle light design showing my new design.

FIG. 2 is a front view of a bicycle light.

FIG. 3 is a rear view of a bicycle light.

FIG. 4 is a left side view of a bicycle light.

FIG. 5 is a right side view of a bicycle light.

FIG. 6 is a top view of a bicycle light; and,

FIG. 7 is a bottom view of a bicycle light.

Any shading and cross-hatching are not features of the design but are utilized to illustrate the surface contours of the bicycle light design in the drawings.

The broken lines in the drawings depict portions of the bicycle light that form no part of the claimed design.
